UNITED STATES PATENT OFFICE.

GEORGE HILL DICKSON, OF EAST NEW YORK, N. Y.

STEAM-ACTUATED VALVE.

SPECIFICATION forming part of Letters Patent No. 319,965, dated June 16, 1885.

Application filed January 22, 1885. (No model.)

To all whom it may concern:

Be it known that I, GEORGE H. DICKSON, of East New York, in the county of Kings and State of New York, have invented a Steam-5 Actuated Valve, of which the following is a specification.

The invention will first be described in connection with the drawings, and then clearly pointed out in the claims.

10 Figure 1 of the drawings is a section through a cylinder and its steam-chest. Fig. 2 is a section at right angles to that of Fig. 1, for the purpose of exhibiting plainly the connection of the exhaust-chamber with the 15 spaces back of the chest-valves. Figs. 3, 4, and 5 are detail views, showing the peculiarities of construction in the intermediate valve.

In the drawings, A represents a steam-chest having the live-steam inlet D, and preferably 20 bored cylindrically.

B' B² are piston-valves operated by the live steam, made hollow at b, to pass the steam down to ports b' b', which connect alternately with the ports ee of the main cylinder E. 25 These valves B' B² have also recesses b' b², which connect the ports ee with the exhaust-channels ff of the exhaust-chamber F, and are notched at b³ b³ on their outer ends, so as to allow the spaces aa and steam-ways I² I³ to 30 register, for feeding exhaust-steam behind the pistons, so as to cushion them at the end of their stroke.

H represents the auxiliary or intermediate valve, which is at the upper part transversely 35 excised, as shown in Fig. 1 of the drawings, and open at the sides for the purpose of allowing a free passage of the steam from inlet D to the cavities of the valves B' B², as clearly shown in Fig. 5. Valve H has the channels 40 I' I⁴, which connect the channels I² I³ with the exhaust-chamber F F', having one part in the bottom of chest and the other in the bottom of valve H.

G represents a toe, which is connected with

the piston, as indicated by dotted lines in Fig. 45 1 of the drawings, so that when the piston C reaches the end of its stroke the toe G is vibrated in the recess F', which forms part of the exhaust-chamber, and causes the valve H to move in a direction opposite to that of the 50 main piston C, so as to make the valves B' B² cover the ports ee of the main cylinder, thus confining enough steam in front of piston C to cushion it. At the same time the channel I' registers with exhaust and space a, while 55 channel I³ registers with the other space, a, and the live-steam space d, so as to admit the steam necessary to give a return-stroke to the valves B' B², which, being rigidly attached together by rod K, must move simultaneously, 60 while the valve H being loose on said rod, the latter moves through it.

Thus it will be perceived that I both cushion the main and the valve pistons by the single movement of the middle valve, which 65 actuates, but is never actuated by, the other valves.

Having thus fully described my invention, what I consider new, and desire to protect by 70 Letters Patent, is—

1. The valves B' B², rigidly connected by rod K, and the intermediate valve, H, loose on said rod, in combination with a chest having inlet D and channels I² I³, the latter so arranged that the steam will not actuate valves 75 B' B² until the main ports are covered, for the purpose specified.

2. In steam-actuated valves, the combination of a chest having the channels I² I³ and live-steam space d, the loose middle valve, H, 80 open on top, having exhaust-space F', and provided with channels I' I⁴, and the piston-valves B' B², having steam-spaces b' b³ and end excisions, b³, as and for the purpose specified.

GEORGE HILL DICKSON.

Witnesses:

JOHN DICKSON,
WM. J. FOSTER.
